(57) **CLAIM**

The ornamental design for a lawn bag funnel, as shown and described.

DESCRIPTION

FIG. 1 is a front view of a lawn bag funnel showing my new design;

FIG. 2 is a rear view of the lawn bag funnel;

FIG. 3 is a right side view of the lawn bag funnel;

FIG. 4 is a left side view of the lawn bag funnel;

FIG. 5 is a top view of the lawn bag funnel;

FIG. 6 is a bottom view of the lawn bag funnel;

FIG. 7 is a top front side perspective view of the lawn bag funnel; and,

FIG. 8 is a top front side perspective view of the lawn bag funnel in use.

The broken lines in FIG. 8 represent environmental structure which forms no part of the claimed design.
